STAND FOR ELECTRIC IRONS

Filed Feb. 10. 1925

INVENTOR.
Harry Taylor.
By *H. Deuelap.* ATTORNEY.

UNITED STATES PATENT OFFICE.

HARRY TAYLOR, OF WHEELING, WEST VIRGINIA.

STAND FOR ELECTRIC IRONS.

Application filed February 10, 1925. Serial No. 8,245.

This invention relates broadly to electric heating appliances, and more specifically to a supporting stand for electrically heated sad-irons.

5 The primary object of the invention is to provide a supporting stand or rest for electric irons, which embodies means whereby, when an iron is seated thereon, the electric circuit to the iron is broken, and, when the 10 iron is removed from the stand, the circuit is re-established, with the ultimate end in view to eliminate the liability to overheating and resultant fire which arises when an iron is left unattended with the heating element turned on.

In describing the invention in detail, reference is herein had to the accompanying drawings, in which—

20 Figure 1 is a view of the invention in top plan with a portion of the cover plate broken away;

25 Figure 2 is a longitudinal section showing the contacts of the stand in circuit closing position; and—

Figure 3 is a similar view, partially broken, showing the parts in circuit opening position.

Referring to said drawings, 1 indicates the bottom, 2 the sides, and 3 the top or 30 cover of a casing which forms the body of the iron-supporting stand. Said cover 3 is preferably removably mounted upon the casing walls, as shown, to afford means of ready access to the interior of the casing.

35 Leading to the interior of the casing through the side walls 2 is a cable 4 embodying two conductor wires 5 and 6, said cable being adapted for connection to a service line, as at a light socket (not shown). One 40 of said conductor wires, as 5, leads directly to one side of a plug socket 7 mounted in the stand at a convenient point, as in the casing walls 2. The other wire 6 is attached to a stationary metallic contact 8 carried 45 interiorly of the casing.

Normally held in underlying engagement with the fixed contact 8 is the free end of a resilient metal contact 9 carried by the casing wall 2, and a conductor wire 10 connects the movable contact 9 to the opposite 50 side of said plug socket 7. Said socket is adapted for the reception of a plug 11 carried by an end of a flexible cord-like conduit 12 which is attached to a sad-iron or 55 other tool to be heated, said conduit having extending therethrough wires (not shown)

leading to the heating coil or the iron, as ordinarily.

Thus, when the movable contact 9 occupies its normal position, shown in Fig. 2 of the drawings, current passes to the heating coil of the iron which has the plug of its attached cord or conduit 12 seated in the plug socket 7, the electric circuit comprising the conductor wire 5, one side of the plug socket 7, one of the wires of the conduit 12, the heating coil of the iron, the other wire of said conduit, the opposite side of said plug socket, the conductor wire 10, the movable contact 9, the fixed contact 8 70 and the wire 6.

The free end of the movable contact 9 overlies a portion of an angular bar 13 which is hinged or pivoted to a fixed support 14 carried at a suitable point interiorly of the casing. Said support has its opposite end pivotally mounted upon a laterally disposed arm or terminal member 15 formed on the lower end of a downwardly inclined rod or link 16 which has its opposite end pivotally attached to the free end of a depressible member 17 which is normally supported in a position in which it projects above the casing cover 3 through a suitably located opening 18 in the latter. As herein shown, said member 17 is of elongated form and has its opposite end pivotally mounted on the under side of said cover. The portion of said member which projects above the level of the cover is of convex form, thus to permit the iron to be advanced unobstructedly thereover by a sliding movement into seated relation to the stand cover.

The depressible member 17 and the there-to-connected parts are yieldingly supported in their elevated positions by a spiral spring 19 which, as herein shown, has its upper end attached at a fixed point on the under side of the cover 3 and its lower end attached to the arm 15 of the link 16. When said member 17 is depressed by a seated iron to the position shown in Fig. 3, the angular bar 13 is swung through the intermediate link 16 to the lowered position shown in said figure, allowing the free end of the movable contact 9 to spring downward out of engagement with the fixed contact 8, thereby to break the electric circuit to the iron. Upon the removal of the iron from the top of the stand, the spring 19 acts to return the parts to their normal posi-

tions, and the contact 9 is returned on the bar 13 into circuit closing engagement with the contact 8 for re-establishing the circuit.

What is claimed is—

5 A stand for electric irons, comprising a casing having associated therewith a socket for the reception of the plug of an electric-iron cord, electrical connections within said casing constituting a current path to said socket, said connections comprising a switch which includes a movable contact, a fixed support underlying said contact, an angular member pivoted to said support and movable to and from a position in which said

contact is elevated to switch-closing position, a member mounted on said casing for vertical movement through the top of the latter, a link intermediate the last mentioned member and said pivoted member adapted, when depressed, to move said pivoted member for actuating the movable contact to circuit closing position, and means normally holding said casing-carried member elevated above the level of said casing top. 15

20 In testimony whereof, I affix my signature.

25 HARRY TAYLOR.
